LOCOMOTIVE STOKER

Samuel G. Jones, Princess Anne County, Va., assignor to Berkley Machine Works and Foundry Company, Inc., Norfolk, Va., a corporation of Virginia

Application October 2, 1939, Serial No. 297,428

8 Claims. (Cl. 110—105.5)

This invention relates to locomotive stokers, and more particularly to stokers of the type that deliver coal to the fire-box through an opening in its backwall.

In stokers of this character coal is fed forward by a conveyor screw from a trough beneath the coal-bin on the locomotive tender and is moved upwardly through an inclined riser conduit to a jet member from which jets of steam distribute the coal over the grate in the fire-box. In stokers which have a conveyor screw in the riser conduit more coal is delivered to the jets at one side of the screw than to those at the other side. This is because the last flight of the screw in passing beneath its hub pushes the coal to one side of the screw and then leaves it there as it passes over the hub back to the opposite side. That is, if the riser screw must be turned in a clockwise direction to convey the coal forward, more coal will be pushed toward the left side of the delivery end of the riser conduit than to the right side. This means that the steam jets will throw more coal toward the left side of the fire-box than toward the right. Heretofore there has been no stoker that is free of this trouble.

It is among the objects of this invention to provide a locomotive stoker which delivers coal to the jet member in substantially equal amounts on both sides of the screw, and which does this by a simple and inexpensive expedient that does not complicate the stoker or increase its size.

In accordance with this invention a trough is mounted on a locomotive tender in a position to receive coal from its coal-bin, and is connected by a tubular conduit and a universal joint to the lower end of an upwardly and forwardly inclined riser conduit. To transfer coal from the tender to the fire-box, conveyor screws are rotatably mounted in the horizontal and inclined conduits with their adjoining ends connected together by universal joints. As the coal leaves the upper end of the riser conduit it passes over steam jets by which it is projected into the fire-box and distributed over the grate. The conveyor screw in the riser conduit has a normal conveyor thread encircling its hub for the major portion of its length but terminating short of its upper end. A reverse thread is mounted on the hub between its upper end and the upper end of the conveyor thread and preferably extends only part way around the hub. This reverse thread is so positioned relative to the conveyor thread that it removes some of the coal from the side of the hub to which the conveyor thread de-

livers the most coal and deposits it on the opposite side of the hub in order to provide substantially equal amounts of coal at both sides of the screw. The upper portion of the riser conduit is enlarged, and the reverse flight, mounted on the tip portion of the screw hub, is buried in the coal in its enlarged portion so that it will not pack coal in the restricted portion of the conduit and interfere with the operation of the stoker. By "tip portion" is meant that portion of the screw hub which is in the enlarged portion of the conduit and which projects above the normal conveyor thread of the screw.

The preferred embodiment of the invention is illustrated in the accompanying drawings in which Fig. 1 is a side view of the front end of my locomotive stoker; Fig. 2 is a front view of the upper end of the stoker taken on the line II—II of Fig. 1; Fig. 3 is a rear view of the riser conduit taken on the line III—III of Fig. 1; and Fig. 4 is an end view of the upper end of the riser screw.

Referring to Fig. 1 of the drawings, a conveyor trough (not shown) is mounted on the locomotive tender in the usual way below its coal-bin in order to receive coal therefrom. Extending forwardly from the front of the trough to a point below the deck 1 of the locomotive cab is a horizontal tubular conduit 2. The front end 25 of the conduit is connected by a suitable universal joint 3 to the lower end of an upwardly and forwardly inclined riser conduit 4 the upper end 20 of which is mounted in rigid position relative to the backwall 6 of the locomotive boiler by bolting the riser to a bracket 7 on the locomotive frame beneath the cab deck.

Coal is fed forward from the trough and through horizontal conduit 2 by means of a conveyor screw 8 that is driven from its rear end 40 by an engine 9 mounted on the locomotive. The front end of this screw is connected by means of a universal joint 11 to the lower end of a conveyor screw 12 rotatably disposed in the riser conduit. As shown in Fig. 3, the lower portion of 45 the riser conduit is tubular, but the upper portion flares out and is enlarged to substantially the width of the normal hand-firing opening 13 above it. The rear wall of the enlarged portion of the riser is flat and is provided with an opening 50 that is normally closed by a clean-out door 14 hinged at its bottom to the conduit and connected at its top to the conduit by bolts 16 pivoted thereto. As shown in Fig. 3, the clean-out door is provided with a row of openings 17 through which the fire-bed may be observed

when slides 18 mounted on the door are moved longitudinally to cause openings 19 therein to register with openings 17.

To distribute coal over the fire-bed after it reaches the upper end of the riser, a hollow jet member 21 is mounted on the upper end of the riser floor which is provided with a forwardly extended flat portion 22 that serves as a support. The jet member is detachably held in place by means of bolts 23 that are threaded in the side walls of the riser and project into depressions in the ends of the jet member (Fig. 2). As shown in Fig. 1, the rear wall of the jet member is inclined and forms a continuation of the adjoining portion of the riser floor, and its front wall is inclined downwardly and forwardly to an apron 24 integral therewith that overlies the bottom of the backwall opening to protect it from possible abrasion. The rear wall of the jet member is inclined downwardly from its center toward its ends as shown in Fig. 2, so that the larger pieces of coal which tend to stay close to the screw hub will roll toward the ends of the jet member and thereby give a better distribution of coal. The lower portion of the jet member is provided with passages connected by pipes 26 to a source of fluid under pressure, such as the steam in the locomotive boiler, and the inclined front wall of the jet member is provided with a plurality of jet orifices 27 from which the steam issues for throwing coal upwardly and forwardly. The inside of the jet member is preferably divided by vertical partitions 28 (Fig. 2) into four chambers to each of which steam is delivered by a separate pipe 26 controlled by a manually operable valve 29 so that the pressure in each chamber can be individually regulated to aid in giving control over fuel distribution.

Coal which is thrown upwardly by the steam jets is intercepted and deflected forwardly in all directions by a fuel-deflecting member 31. The deflector is supported from its rear end by a substantially horizontal shaft 32 extending therethrough and pivotally mounted in lugs 33 depending from the top wall of the riser conduit. To prevent this shaft from turning in the deflector and yet permit it to be readily withdrawn from the latter in case it is desired to remove the deflector, the central portion of the shaft is preferably noncircular in cross section and the shaft-receiving passage through the deflector is the same shape. The exposed end of the shaft is provided with a lever 34 for turning it in order to swing the deflector in a vertical plane, and the lever is locked in adjusted positions by any suitable means, such as a toothed segment 36 secured to the side of the riser and engaged by a retractile spring-pressed pin 37 connected to the lever in a well-known manner (Fig. 3).

To distribute coal uniformly over the fire-bed the lower surface of the deflector in the path of coal thrown against it by the steam jets is provided with a plurality of depending fuel-guiding ribs. Preferably there is a pair of forwardly and outwardly curved ribs 38 for directing coal to the side portions of the grate near its rear end. By adjusting the deflector vertically by means of lever 34, and by adjusting steam jet valves 29, any desired distribution of coal can be obtained.

It is a feature of this invention that substantially the same amount of coal is fed to the jet member on both sides of the riser screw. Accordingly, the normal conveyor thread 41 which extends upwardly from the lower end of the riser screw terminates at a point a few inches short

of the upper end of the screw hub 42 which is substantially in a plane passing across the top of the jet member and the bottom of the clean-out door opening. The screw shown in the drawings 5 is turned in a clockwise direction to raise the coal through the riser conduit, and consequently thread 41 tends to push more coal toward the left of the riser outlet than toward the right. Some of the excess coal thus deposited on the 10 left side of the screw hub is carried over to the opposite side of the hub by means of a reverse flight 43, that is, a screw flight which extends around the hub in a direction opposite to that of the main thread. The reverse flight tends to push the coal backwardly against the main flight, and between the opposing forces of these two flights coal is picked up, carried over the hub and deposited in the less dense coal on the opposite side of the hub to thereby equalize the 15 amount of coal on both sides of the hub. The reverse flight is located in the coal up in the enlarged portion of the riser conduit so that it will not pack coal in the restricted lower portion of the conduit. To prevent the reverse flight from 20 packing the coal too tightly between it and the adjacent end of the main thread it extends only part way around the hub with its ends tapering into the hub as shown in Fig. 4, and its high point 25 A is spaced from the opposite high point B (the point in axial alignment therewith) of the main thread a distance at least as great as the pitch of the latter. Also, the outer end of the reverse thread is disposed substantially opposite the delivery end of the conveyor thread. With the 30 reverse thread positioned in this manner on the screw hub some of the coal is transferred from one side of the screw to the other without packing in the screw or in the conduit. As a further 35 precaution against packing the reverse thread tapers in thickness away from the hub so that it will cut through the coal like a knife.

According to the provisions of the patent statutes, I have explained the principle and mode of operation of my invention and have illustrated 45 and described what I now consider to represent its best embodiments. However, I desire to have it understood that, within the scope of the appended claims, the invention may be practiced otherwise than as specifically illustrated and described.

I claim:

1. A locomotive stoker riser conveyor screw for use in an inclined riser conduit having an enlarged upper portion, said screw being adapted 55 to raise coal through the conduit to a jet member at its upper end, the screw comprising a hub, a conveyor thread encircling the hub for the major portion of its length and terminating short of its delivery end, and a reverse thread mounted on the hub at its tip portion between its delivery end and the adjacent end of said conveyor thread, said reverse thread being adapted to be disposed in the enlarged upper portion of the riser conduit, whereby the screw is adapted to deliver coal substantially uniformly on both sides of the screw.

2. A locomotive stoker conveyor screw for use in an inclined riser conduit to raise coal there-through to a jet member at the upper end of the conduit, said screw comprising a hub, a conveyor thread encircling the hub for the major portion of its length and terminating short of its delivery end, and a reverse thread mounted on the hub between its delivery end and the adjacent end of said conveyor thread and extending only 70 part way around the hub, whereby the screw is

adapted to deliver coal to the jet member substantially uniformly on both sides of the screw without harmful packing of the coal between said threads.

3. A locomotive stoker conveyor screw for use in an inclined riser conduit to raise coal there-through to a jet member at the upper end of the conduit, said screw comprising a hub, a conveyor thread encircling the hub for the major portion of its length and terminating short of its delivery end, and a reverse thread mounted on the hub between its delivery end and the adjacent end of said conveyor thread and extending only part way around the hub, at least half of said reverse thread being spaced from the opposing portion of said conveyor thread a distance at least as great as the pitch of the conveyor thread, whereby the screw is adapted to deliver coal to the jet member substantially uniformly on both sides of the screw without harmful packing of the coal between said threads.

4. A locomotive stoker conveyor screw for use in an inclined riser conduit to raise coal there-through to a jet member at the upper end of the conduit, said screw comprising a hub, a conveyor thread encircling the hub for the major portion of its length, the delivery end portion of said thread tapering into the hub at a point spaced from the adjacent end thereof, and a reverse thread extending only part way around the hub between its delivery end and the adjacent end of said conveyor thread with its ends tapering into the hub, whereby the screw is adapted to deliver coal to the jet member substantially uniformly on both sides of the screw.

5. A locomotive stoker conveyor screw comprising a hub, a conveyor thread encircling the hub for the major portion of its length, the delivery end portion of said thread tapering into the hub at a point spaced from the adjacent end thereof, and a reverse thread extending only part way around the hub between its delivery end and the adjacent end of said conveyor thread with its ends tapering into the hub, the high point of the reverse thread being spaced from the opposite high point of the conveyor thread a distance at least as great as the pitch of the latter, and the outer end of said reverse thread being disposed substantially opposite the delivery end of said conveyor thread.

6. In a locomotive stoker, a riser conduit hav-

ing an enlarged upper portion, a jet member connected to said upper portion, a screw rotatably mounted in the conduit and provided with a conveyor thread for raising coal through the conduit and delivering it to the jet member, said screw being adapted to be driven from its lower end and having a free upper end, said thread terminating short of the upper end of the screw, and said screw being provided at its tip portion in said enlarged portion of the conduit with a reverse flight between its upper end and the adjacent end of the conveyor thread, said reverse flight being adapted to be substantially completely buried in the coal in the conduit, whereby coal is delivered substantially uniformly to the jet member on both sides of the screw.

7. In a locomotive stoker, a riser conduit having an enlarged upper portion, a jet member connected to said upper portion and having a top wall inclined downwardly from its center toward both sides of said conduit, a screw rotatably mounted in the conduit and provided with a conveyor thread for raising coal through the conduit and delivering it to the jet member, said screw being adapted to be driven from its lower end and having a free upper end, said thread terminating short of the upper end of the screw, and said screw being provided at its tip portion in said enlarged portion of the conduit with a reverse flight between its upper end and the adjacent end of the conveyor thread, said reverse flight being adapted to be substantially completely buried in the coal in the conduit, whereby coal is delivered substantially uniformly to the jet member on both sides of the screw.

8. A locomotive stoker conveyor screw for use in an inclined riser conduit having an enlarged upper portion, said screw being adapted to raise coal through the conduit to a jet member at its upper end, the screw comprising a hub, a conveyor thread encircling the hub for the major portion of its length and terminating short of its delivery end, and a relatively short reverse thread mounted on the hub between its delivery end and the adjacent end of said conveyor thread, said reverse thread being so positioned on said hub as to be restricted to the enlarged upper portion of the riser conduit, whereby the screw is adapted to deliver coal substantially uniformly on both sides of the screw.

SAMUEL G. JONES.
